LEO J. GRUBMAN, OF BELLE HARBOR, NEW YORK

MEANS FOR MAKING ARTIFICIAL EYES FOR DOLLS

Application filed December 17, 1926. Serial No. 155,441.

This invention relates to an improved means for making artificial eyes for dolls, display figures or other manikins, and has particular reference to the accurate formation of the individual artificial eye members for a sleeping doll whereby the pupils of the respective eye members will be properly centered with relation to the eye openings in the wall of the doll head, notwithstanding the possible non-symmetrical formation of said head wall or the inaccurate formation of the eye member.

Essentially, my present invention consists in first forming a sheet of celluloid, sheet metal or other ductile material having an eye pupil delineated thereon into a hollow shell, then adjusting the shell upon a suitable support to position the eye pupil relative to a plane intersecting the geometric axis of the shell as determined by the particular relation to the eye opening in the doll head wall with respect to a perpendicular plane parallel to the axis of oscillation of an oscillatory eye setting; and thereafter providing the eye member with means located in said plane, to engage a part of the eye setting movable about the axis of oscillation. Thus when oscillatory motion is transmitted to the eye member by the eye setting mounted on the doll head wall by reason of contact of the eye shell with said part of the setting, the eye pupil will be centrally positioned in the eye opening of the head wall notwithstanding the fact that the horizontal axis of said opening is not parallel with the axis of oscillation so that said eye pupil will move centrally between the opposite ends of the eye opening. Also, it will be apparent that the two eye members will bear a proper relation to each other as well as to the respective eye openings.

The invention also has for a further object to provide simple and easily operable means for adjusting the eye shell on a support and producing slots or recesses in the edge of the shell wall in definite relation to the eye pupil which are adapted to receive suitable holding means whereby the eye shell is properly positioned for the engagement of the edge of the shell by the trimming tool.

With the above and other objects in view, the invention consists in the improved method and means for making artificial eyes and in the several novel features of the apparatus employed, as will be hereinafter more fully described, illustrated in the accompanying drawings and subsequently incorporated in the subjoined claims.

In the drawings, wherein I have disclosed a suitable example of mechanism or apparatus for carrying out my improved method, and in which similar reference characters designate corresponding parts throughout the several views,

Figures 1 and 2 are fragmentary sectional views illustrating a suitable form of shaping die for producing the individual eye shells;

Fig. 3 is a top plan view of the machine for positioning and holding the eye member on a suitable mandrel or support and providing the edge of the eye shell with slots or recesses in accurate relation to the eye pupil;

Fig. 4 is a vertical sectional view taken on the line 4—4 of Fig. 3;

Fig. 5 is a front elevation of the machine;

Fig. 6 is a longitudinal sectional view illustrating the machine for trimming the rear edges of the eye shells;

Fig. 7 is a fragmentary horizontal section through a doll head showing the two oscillating eye members mounted therein, and said head being of non-symmetrical form;

Fig. 8 is an enlarged detail plan view showing one of the eye members as arranged in conjunction with the pupil sighting means for providing the eye member with properly located surfaces for engagement with a part of an eye setting;

Fig. 9 is a plan view showing the two eye members as produced in accordance with my new method assembled upon the rectangular axis of an eye setting;

Fig. 10 is a front elevation thereof, and

Fig. 11 is a side elevation illustrating the different relations which the longitudinal center lines through the two eye members bear with respect to the centers of the pupils thereon.

Heretofore artificial eyes for dolls have

been produced in the form of shells die pressed from celluloid, sheet metal or other ductile or workable material. The eye pupil and the upper eyelid are printed or otherwise delineated upon one side of the sheet material before it is subjected to the die pressure and formed into a shell. It not infrequently happens, that due to structural inequalities in the material, or to unequal resistance to the drawing pressure, after the shell has been formed, the eye pupil is found to be offset or in eccentric relation to the longitudinal axis through the wall of the substantially semi-spherical eye shell. Therefore, when this shell is mounted upon the pivotally supported pendulum in the doll head, the eye pupil will not, in the open position of the eye be centered in the opening in the doll head wall, assuming that the horizontal axis of this opening is parallel to the axis of oscillation. Also, the centers of the eye pupils of the two spaced eye members may not be located in the same horizontal plane, but the pupil center of one member may be in differently spaced relation from the eyelid at the upper edge of one eye opening than the center of the pupil of the other eye member with respect to the eyelid of the other eye opening.

Again, in the molding of the doll heads, precisely the same form and contour of the head wall surrounding the eye openings at opposite sides of the nose may not be produced, or in other words these parts of the head wall structure may be non-symmetrical. Therefore, in this case, even though the eye pupil, in the drawing of the shell may be exactly concentric with the axial center line of the shell, since the major axis of the eye opening in the head wall is out of parallel relation to the axis of oscillation of the eye member when it is mounted in the head, the eye pupil will not be centered in said opening. Thus in these cases, the simulation of the movement of a normal human eye is practically destroyed and it has heretofore been necessary, to provide an adjustable or universally swivelling connection between the individual eye members and the part of the eye setting by which they are carried. This results in added expense in the manufacture of such devices and also in an appreciable loss of time in the operation of properly applying the eye mounting to the doll head, and which operation necessitates the employment of highly skilled workers in the art. It is the purpose of my present invention to overcome these difficulties which the prior art has experienced in the manufacture of sleeping dolls and similar figures.

In order to enable the several advantages of my present disclosure to be fully understood and appreciated, in Fig. 7 of the drawings I have shown a horizontal section 65 through the front portion of a doll head 5.

The doll head wall is produced under pressure from wood pulp, papier mâché or other composition material in a desired cross sectional form by means of a suitable mold. It is not an infrequent occurrence that owing to the non-symmetrical disposition of the facial features in the original sculpture from which the mold is produced, that the corresponding features of the doll head after removal from the mold, of course, are in like non-symmetrical relation with respect to a central plane bisecting the doll head structure. Therefore, after the eye openings 7 are cut through the front wall of the doll head and said wall at the inner sides of these openings milled out to provide the concave sockets 8, the major axes of the elliptical shaped eye openings will be found not to extend in alignment with each other or in parallel planes. This inaccuracy in the molding of the doll head is clearly illustrated in Fig. 7 of the drawings.

Upon the inner side of the front wall of the doll head the supporting shaft 9 for the eye mounting is suitably secured with its axis extending in parallel relation to said front wall. The eye mounting including a plate or frame 10 of suitable form is suspended from this shaft. The eye members or shells generally indicated at 11 are positioned between the plate 10 and the respective sockets 8, the rear edges of said shells being engaged by the plate 10 whereby oscillatory movement is transmitted to said eye shells in the swinging movement of the plate on the supporting shaft 9. It will be evident that if the shells 11 are all of one standard form or shape with the eye pupil 12 and the eyelid 13 properly painted thereon so that a line through the center of the eye pupil extends at right angles to the axis of oscillation of the shell, that while the eye pupil would be properly centered in one of the eye openings 7 the horizontal axis of which is parallel with the axis of oscillation as shown at the left hand side of Fig. 7, the eye pupil of the other shell would be in eccentric relation to the center of the other eye opening 7, as the horizontal axis of this eye opening, as shown at the right hand side of Fig. 7, and indicated by the broken line A, is out of parallel relation to the axis of the shaft 9. In other words, in order to obtain an accurate location of the eye pupil with relation to the edges of this opening 7, it is necessary that the center line through the eye pupil indicated at B shall intersect the axis of oscillation at the geometric center of the shell and extend at right angles to the major axial line A of the eye opening. Therefore, it is apparent that the eye shell to be associated with this latter opening cannot be of the same standard form or shape as the eye shell associated with the left hand opening of the doll head wall.

In Figs. 1 and 2 of the drawings I have 130

shown a conventional form of drawing die whereby the sheet material is drawn into shell form. Thus the sheet of ductile material S is seated in a recess in the upper surface of the die plate P over the opening O therein. A pressure ring R is engaged upon the outer edge portion of said sheet S and a male drawing die D is adapted to be moved downwardly under pressure through the ring R and into the opening O, thus drawing the sheet S downwardly into said opening against the frictional resistance of the pressure ring R. As indicated in Fig. 2 of the drawings, due to unequal resistance of the ring R to the drawing pressure of the die member D, after the shell is formed, the eye pupil 12 which was initially accurately centered on the surface of the sheet S with respect to the axis of the drawing die may be found to be in eccentric relation to the center line of the semi-spherical wall of the shell. This also would of course, result in an inaccurate centering of the eye pupil in the openings of the doll head wall, even though the major axis lines A of said openings are in exact parallelism with the axis of oscillation.

In order to rectify these above referred to mechanical inaccuracies either in the formation of the individual eye members or in the structure of the doll head wall, in one embodiment of the invention, I propose to cut or trim the rear edge of the eye shell so that it will be disposed in a required plane with respect to a plane intersecting the geometrical axis of the eye shell and the center of the eye pupil whereby the latter will be accurately centered in the individual eye openings of the doll head wall by contact of the rear edge of the shell against the front face of the suspended pendulum plate 10 through the medium of which the eye shell is oscillated. To this end, in Figs. 3, 4 and 5 of the drawings, I have shown an apparatus for providing the shell wall at opposite sides thereof and in spaced relation to its rear edge with suitable openings to receive the shaft 9 and with additional slots or recesses in predetermined relation to the eye pupil 12. This machine includes a suitable table or bed plate 14 on the upper end of a supporting frame structure 15, said bed plate having an opening 16 into which an arm 17 projects from one side thereof. In this arm a hollow supporting post or mandrel 18 is vertically positioned and rigidly fixed by the set screw 19. The upper end of this hollow post is of semi-spherical form as clearly shown in Fig. 4 of the drawings. The wall of said post is provided in opposite sides thereof and in line with the axis of its semi-spherical upper end with the circular openings 20. The post wall is further provided with a plurality of spaced vertically extending slots 21 therein, the purpose of which will be presently explained.

In line with the arm 17, the table 14 is provided with a concave seat 22 to receive a rocker member 23, said member having a circumferential groove 24 to receive a rib 25 at the outer side of the seat 22. Stop screws 26 are threaded in the table 14 and the heads on the upper ends of these screws are adapted to extend over the opposite ends of the rocker member 23 and constitute stops limiting the rocking movement of said member in each direction.

This rocker member carries an upwardly extending cylindrical post 27 upon which a sleeve 28 is loosely engaged for vertical movement, said sleeve at its lower end having an arm 29 integrally formed therewith and projecting inwardly above the arm 17. The end of this arm 29 is provided with a recess having concave rear and side walls indicated at 30 extending downwardly from a sight opening 31 in the upper part of said arm. The curvature of the concave walls 30 corresponds with the curvature of the semi-spherical eye shell.

A rod 32 is threaded at its lower end in the arm 29 adjacent to the sleeve 28 and at its upper end is loosely engaged through an opening in an arm 33 fixed on the upper end of the post 27. A coil spring 34 surrounds the rod 32 between the arm 33 and the arm 29 and yieldingly resists upward movement of said arm and the sleeve 28 relative to the fixed post 27.

The forward end of the rocker member 23 is formed with a bifurcated lug 35 in which the lower end of a link 36 is pivoted, the upper end of said link being pivotally connected as at 37 to the forked end of a lever 38. The forks of this lever straddle the sleeve 28 and are pivotally connected with the opposite sides thereof as at 39. It will thus be apparent that upon depressing the end of the lever 38, the sleeve 28 with the arm 29 may be lifted against the action of the spring 34. It will further be understood that the member 23 together with the arm 29 and parts mounted upon said member may be laterally rocked on the table, said rocking movement taking place about an axis which intersects the center of the semi-spherical upper end of the post 18 so that the concave surfaces 30 on the end of the arm 29 will move in an arc concentric with the semi-spherical surface of the upper end of said post. As shown in Fig. 5, the heads of both of the screws 26 are engaged with the rocker member 23, thus locking said member against movement. In order to move the operating lever 38 and the arm 29 from the neutral position indicated in Fig. 5, one or the other of said screws is adjusted to position the head thereof above the rocker member, thereby permitting of a rocking movement of said member in one direction to a limited extent. For the purpose of accurately determining the degree of rocking lateral move-

ment of the arm 29 in one direction or the other, I provide a suitable gauge consisting of an index arm 40 fixed at one of its ends to the outer end of the rocker member 23 and having its other end positioned contiguous to the graduated edge 41 of the gauge plate 42 which is fixed to the edge face of the table 14.

Upon the upper surface of the table 14 spaced guide ways 43 are provided, the number of said guide ways corresponding to the number of the slots 21 in the wall of the post 18. Slides 44 are mounted in these guide ways. The opposed slides at opposite sides of the arm 17 are provided centrally of their ends with the longitudinally projecting punches 45 and in spaced relation to each of said punches with a suitably formed cutting bit 46. The other slide 44 also has a cutting bit 47 projecting centrally from its end, but is not provided with a punch 45.

The slides 44 may be simultaneously actuated by any desired mechanism, and for this purpose I have shown in the accompanying drawings, two bell crank levers 48 pivotally mounted in opposed relation to each other as at 49 in the frame structure 15. The upwardly extending arms of these levers are engaged with the outer ends of the opposed slides having the punches 45 and the other horizontally extending arms of said levers are positioned in overlapping relation and have slidably contacting cam surfaces 50. To the upper lever arm the upper end of a vertical rod 51 is connected, the lower end of which may be operatively connected with a suitable treadle. A coil spring 52 having its upper end secured to the frame structure 15 has its lower end attached to the lower horizontal arm of the other bell crank lever, said spring acting to yieldably hold said levers in the normal position shown in Fig. 5 of the drawings.

Motion is transmitted from one of the opposed slides 44 above referred to to the third slide 44 by any convenient mechanical means, such as the two lever members 53 mounted upon the upper side of the table 14 and respectively connected with the two slide members and cooperating with each other. Thus, it will be understood that when the rod 51 is pulled downwardly, the two levers 48 are rocked and their vertically extending arms are moved inwardly thus forcing the opposed slides 44 inwardly, and also transmitting a similar inward movement through the levers 53 to the other slide 44. As will be later explained in more detail, the punches 45 and the bits 46 and 47 carried by these slides are thereby caused to produce circular openings in opposite sides of the eye shell to receive the shaft 9 and additional slots or recesses in the rear edge of said shell and in definite predetermined relation to the eye pupil on the surface thereof.

In the operation of the above described apparatus, after the eye shell has been drawn in

the manner shown in Figs. 1 and 2 from the sheet of celluloid or other material, it is arranged upon the supporting mandrel 18 as shown in Fig. 4 of the drawings, the lever 38 being manipulated to lift the arm 29 so that after the eye shell is placed on said mandrel and the lever 38 released, the arm 29 will clampingly hold the eye shell upon the semi-spherical upper end of said mandrel, the shell being properly adjusted beneath the arm so that the pupil 12 on the eye shell appears in substantially concentric relation to the lower edge of the sight opening 31 in the end of the arm 29. If the front wall of the doll head is non-symmetrical and the long axis of the eye opening therein out of parallel relation to the plane of said wall as indicated at the right hand side of Fig. 7, this error is accurately calculated. The arm 29 is then lifted and laterally rocked by means of the handle lever 38 to the proper extent which will be indicated on the degree scale 41 by the arm 40, such rocking movement being limited by one or the other of the stop screws 26. The eye shell is then shifted upon the upper end of the mandrel 18 and the pupil of said eye member positioned with respect to the plane of movement of the punches 45 and cutting bits 46 and 47 and with relation to the lower edge of the sight opening 31. The slides 44 are then simultaneously actuated as above explained so that the shaft receiving openings 11' are formed in the opposite sides of the eye shell wall by the punches 45 which enter the openings 20 in the wall of the mandrel 18. Simultaneously the slots or recesses 11^a are cut in the edge of the eye shell by the cutting bits 46 and 47. The closed inner ends of these recesses are thus located in definite predetermined relation to the eye pupil 12. After thus providing the eye shell with the openings 11' and notches or recesses 11^a, the holding arm 29 is lifted and the eye shell removed from the mandrel.

The next operation is to trim or cut the edge of the eye shell at its open end so that it will extend in parallel relation with the inner ends of the notches or recesses 11^a and thus in the same definite relation to the eye pupil 12. For this purpose, I employ a trimming tool or machine, one embodiment of which I have shown in Fig. 6 of the drawings. Referring to this figure, a hollow shaft 53 is mounted in spaced bearings, (not shown), supported in a suitable frame structure partially illustrated at 54. To one end of this shaft cutting blades 55 are suitably fixed. Said shaft may be driven by a belt engaged with the wheel 56 fixed on said shaft or by any other suitable driving connections between said shaft and a convenient source of power.

A rod 57 is axially movable through said shaft 53, one end of said rod being slidably guided in a suitable opening 58 provided in the machine frame and said end of the rod

slotted to receive a transverse pin 58 fixed in said frame and whereby said rod is held against rotation. An adjustable stop screw 60 is threaded in the frame in line with this 5 end of the rod 57 and by contact therewith limits the sliding movement of said rod in one direction.

The other end of the rod 57 has a threaded bore to receive the threaded stem or shank 62 10 of a semi-spherical supporting member 61, the diameter of which is such as to snugly fit within the eye shell. At its inner end this member 61 is provided with the radially projecting lugs 63 corresponding in number and 15 in the spacing thereof with the arrangement of the slots 21 in the mandrel or post 18 and therefore, with the arrangement of the notches or recesses 11^a which are cut in the wall of the eye shell. Therefore, it will be 20 evident that when the eye shell is arranged upon this support 61 and the lugs 63 thereof engaged in the respective notches or recesses 11^a, said eye shell is held against turning movement on said support and with the pupil 25 of said shell bearing identically the same relation with respect to the geometrical center of said semi-spherical support as it bore with relation to the center of the upper semi-spherical end of the mandrel 18 when the 30 notches or recesses 11^a were cut in the shell wall.

A presser block 64 on the end of a rod 65 35 which may be operated by a foot treadle or other suitable means is now engaged with the eye shell, said block having a cavity 66 in its end face of corresponding diameter with the external diameter of the eye shell wall. After proper adjustment of the stop screw 60, said presser member is actuated to axially 40 move the rod 57 against the action of a coil spring 67 which is interposed between a part of the machine frame and a collar 68 fixed on said rod, and thereby engage the edge of the eye shell wall with the face of the rotating cutting blades 55. The pressure 45 is continued until the end of rod 57 contacts with the stop screw 60, at which time the said edge of the eye shell wall will have been trimmed down until all portions thereof extend in a plane which is parallel with the inner 50 end edges of the notches or recesses 11^a engaged against the lugs 63. The pressure against rod 57 is then released and the rod is returned to its normal position by spring 55 67. The eye shell is then removed from support 61.

From reference to Fig. 7 of the drawings, it will be seen that when the two eye shells are arranged upon the front side of the 60 weighted frame plate 10 with the supporting shaft 9 extending through apertured parts of said plate and through the coinciding openings 11' in the walls of the eye shells, the rear edge of each shell is in contact with 65 the face of the plate 10 whereby an oscillatory

motion is transmitted to the eye shell in the swinging movements of said plate. Owing to the fact that the relation between the center of the eye pupil and the rear edge of the eye shell has been accurately predetermined for each individual shell in accordance with the possible non-symmetric contour of the head wall at the eye openings therein, such contact of the rear edge of the shell against the frame plate 10 insures a proper 70 relationship between the pupils of the individual eye members and the walls of the respective eye openings when the eye mounting is arranged within the doll head and applied or attached in operative position on the front 75 wall thereof. Thus in the oscillating movements of the pendulum support which are transmitted to the eye members, a natural and realistic simulation of the movements of the pupils of the human eyes will result, notwithstanding the mechanical inaccuracies 80 above referred to. In so far as I am aware, I am the first in this art to provide a method and means for accomplishing this purpose and thereby eliminating losses incident to 85 waste of time and materials with a corresponding saving of manufacturing costs and a decided improvement in the functioning of the assembled parts.

The mechanical means which I have above 90 described for adjustably holding the eye shells and providing the recesses 11^a therein and for trimming the rear edges of the eye shells are largely suggestive, and it will be understood that the fundamental feature of 95 my present disclosure resides in the method of making such eye shells whereby the mechanical inaccuracy in the form of the shell or in the structure of the doll head may be properly taken care of so that after the 100 assemblage of the eye mounting in the doll head the accurate and realistic movement of the eye pupils in the respective eye openings will be assured without necessitating any further independent adjustments of the individual eye members.

In Figs. 8 to 11 of the drawings, I have 105 illustrated another embodiment of the invention wherein the eye members are adapted to be mounted in fixed relation to the axis of the eye setting, said eye members being provided with surfaces in predetermined location to the pupil center in accordance with the location of a surface on the shaft or axis 110 with respect to the point of intersection of the major and minor axes of the eye opening in the doll head wall within which the eye setting is adapted to be mounted. Preferably, I use an oscillatory shaft or axis for the eye members which is of rectangular 115 form in cross section, as shown in my co-pending application for patent filed December 9, 1926, Serial No. 153,485.

As shown in Fig. 8 of the drawings, after 120 the eye shell has been arranged upon the sup-

port 18 and the sighting member or arm 29 properly adjusted and the pupil on the surface of the eye member centered in relation to the sight opening in the end of said arm as above explained, while the eye member is 5 clampingly held by the arm 29, the square punches or cutters 45' are simultaneously operated to provide the opposite sides of the shell wall with correspondingly shaped openings 11^b therethrough, thus definitely locating these openings with respect to the pupil center. In this form of the invention, the tool elements 46 above referred to which provide the slots 11^a in the wall of 10 the eye shell are not used, as it is unnecessary to trim the edge of the eye shell at its rear 15 open end.

The shaft or axis of the eye setting as shown at 9' is of general rectangular form, 20 substantially corresponding in size with the size of the openings 11^b so that the edges of said openings will have close fitting contact with the surfaces of the shaft or axis. This shaft at opposite sides of its center is 25 provided with a cylindrically turned portion indicated at 9^a, said cylindrical portions being adapted for engagement upon suitable bearing seats provided upon a suitably formed supporting member attached to the 30 doll head wall, as disclosed in my co-pending application above referred to.

It will be apparent from the above that although the pupil center may be either horizontally or vertically offset with respect to 35 the longitudinal axial center line of the shell due to the inaccurate drawing of the shell, and although the major axial line of the eye opening in the doll head wall may be out of parallel relation with the axis of oscillation of the eye setting due to a non-symmetrical formation of the head, such inaccuracies may be readily taken care of by the 40 adjustable sighting device for the eye pupil to definitely locate the openings 11^b through 45 the shell wall in relation to the pupil center. Thus, as shown in Figs. 9 and 11 of the drawings, when the two eye members are mounted upon the opposite ends of the rectangular shaft 9' of the eye setting, the co- 50 acting surfaces of the shell wall and of said shaft fixedly hold the eye members in definite relation to each other so that the pupil of each eye member will assume a predetermined position with relation to the pupil 55 of the other eye member and also with relation to the opening in the wall of the doll head with which the eye member is associated. In Fig. 9 of the drawings, the line "B" is the axial center line of the eye shell 60 while the line "C" indicates a plane at right angles to the axis of shaft 9' and intersecting the center of the eye pupil and also intersecting the shell axis B at its point of intersection with the axis of said shaft. Therefore, 65 it will be understood that in drawing the eye

shell, the pupil center was found to be in horizontally offset relation to the axial line B.

In Fig. 11, the two eye shells are shown, the pupil center of one eye shell being vertically offset in one direction from the longitudinal axis B of the shell while the pupil center of the other shell is vertically offset in the opposite direction from the axial line of the latter shell. Nevertheless, by the provision of the sighting means for the eye pupil and the means for providing said shell wall with surfaces definitely located with respect to the pupil to cooperate with a corresponding surface on a part of the eye mounting, the pupil centers of these two eye members are located exactly in the same horizontal plane as indicated by the line E in Fig. 11.

At the left hand side of Fig. 9 of the drawings, an accurately drawn eye shell is shown with the pupil center coinciding with the longitudinal center line C through the shell, and from a comparison of this left hand shell with the right hand shell in Fig. 9, the different location of the shaft receiving openings in the walls of the two shells with respect to the pupil centers will be readily apparent. By thus definitely locating said shaft engaging surfaces for each individual shell, 95 the line C intersecting the pupil center at right angles to a plane tangent to said pupil center of the inaccurately drawn shell is precisely parallel with a similar line at right angles to said plane and intersecting the pupil 100 center of the other accurately drawn eye shell. Since, in this form of the invention, the additional operation of trimming the rear edge of the eye shell will be eliminated, it will preferably be employed and in conjunction 105 with my new eye mounting as disclosed in the co-pending patent application makes it possible to very greatly expedite the operation of assembling the eye members upon the oscillatory eye setting and mounting the setting 110 within the doll head with the individual eye members having their pupil centers in accurate registration with the minor axes of the openings in the doll head wall and bearing 115 precisely the same positions relative to the upper and lower edges of said openings.

In the practice of my present improvements, it is contemplated that other mechanical means might possibly be utilized for the above purposes, and it is accordingly to be 120 understood that as to this part of my present disclosure, I reserve the privilege of incorporating the same in various other alternative structures as may be fairly considered within the spirit and scope of the invention as 125 claimed.

I claim:

1. Apparatus for the purpose described including a fixed support upon which a hollow artificial eye member having a pupil thereon 123

is adapted to be engaged, an adjustable sight associated with said support and with respect to which the pupil of said eye member is adapted to be located and the pupil center thereby positioned in definitely predetermined relation to planes bisecting the eye member in perpendicular relation to each other, and tool elements operatively movable with respect to said support at opposite sides thereof to provide the wall of said eye member with openings therethrough in definite relation to the pupil center adapted to receive the shaft or axis of an oscillatory eye mounting.

2. Apparatus for the purpose described including a support, means adjustable relative to said support for holding an eye member having a semi-spherical end with an eye pupil thereon upon the support and with the center of the pupil in predetermined relation to a bisecting plane normal to the longitudinal axis of the eye member, said means including a part movable in a path concentric with the end of the eye shell and with respect to which the shell is adapted to be adjusted on the support and means operating upon the eye member while it is so held to provide said eye member with means adapted to cooperate with a part of an oscillatory eye mounting to retain the eye member in cooperative relation with an eye opening in a doll head wall with the center of the eye pupil thereon in approximate registration with the minor axis of said opening.

3. Apparatus for the purpose described including means for holding an eye member having a semi-spherical end with an eye pupil thereon and with the center of the pupil in predetermined relation to a bisecting plane normal to the longitudinal axis of the eye member, said means including a part movable in a path concentric with the end of the eye shell and with respect to which the shell is adapted to be adjusted, means for yieldingly urging said part into clamping engagement with the eye shell wall, manually operable means for disengaging said part from the eye shell and means for simultaneously providing the opposite sides of said eye member with aligned means located in a plane at right angles to a plane intersecting the pupil center for the connection of said eye member with the shaft or axis of an oscillatory eye mounting.

4. Apparatus for the purpose described including a support to receive an eye shell provided with an eye pupil, means for holding the shell in position upon said support with the center of the pupil in predetermined relation to the longitudinal axis of the support in accordance with the angular relation between the major axial line of an eye-shaped opening in the wall of a doll head and the axial center of an oscillatory mounting for the eye adapted to be arranged in said head,

said means including a part mounted for movement about an axis extending in right angular intersecting relation with the axis of the support, means for mounting said part for radial movement with respect to its axis of oscillation, and means yieldingly urging said part radially towards the support and into clamping engagement with the eye shell and means operable while the eye shell is held in such adjusted position on the support to provide said shell at opposite sides thereof with means for connection of the shell in supported relation to the axis of the eye mounting whereby said shell will be supported with its pupil center in approximate registration with the minor axis of the opening in the doll head wall.

In testimony that I claim the foregoing as my invention, I have signed my name hereto.

LEO J. GRUBMAN.
